CLAIM

The ornamental design for a handle for laparoscopic device with distal rotation wheel, as shown and described.

DESCRIPTION

FIG. 1 is a perspective view of a handle for laparoscopic device with distal rotation wheel in accordance with the present design;

FIG. 2 is a rear view of the handle for laparoscopic device with distal rotation wheel of FIG. 1;

FIG. 3 is a front view of the handle for laparoscopic device with distal rotation wheel of FIG. 1;

FIG. 4 is a top view of the handle for laparoscopic device with distal rotation wheel of FIG. 1;

FIG. 5 is a bottom view of the handle for laparoscopic device with distal rotation wheel of FIG. 1;

FIG. 6 is a left side view of the handle for laparoscopic device with distal rotation wheel of FIG. 1; and,

FIG. 7 is a right side view of the handle for laparoscopic device with distal rotation wheel of FIG. 1.

In the drawings, the broken lines depict environmental subject matter only and form no part of the claimed design.
